WINDOW CONSTRUCTION

Roy T. Axe, Syracuse, N. Y., assignor to The O. M. Edwards Company, Syracuse, N. Y., a corporation of New York

Application January 30, 1939, Serial No. 253,472

6 Claims. (Cl. 189—64)

This invention relates to window constructions, and has for its object a particularly simple adapter by which two spaced apart glass panels may be supported in a conventional sash intended for supporting one glass panel, which adapter is simple and economical in construction, readily applied to the sash without modifying or materially modifying the sash.

Modern air-conditioning for railway cars, buses and other vehicles and enclosures has developed so rapidly that there are many railway cars, buses, etc., that are comparatively modern in all respects, except for the double windows necessary, or highly desirable, in air conditioned enclosures. The sash equipment of such cars or vehicles is comparatively new and the expense of discarding them for new double sashes is oppressive. Therefore, the object of the invention is an adapter by which such single sash may be readily and economically adapted for supporting a double glass panel.

The invention comprises, generally, an adapter for supporting a second glass panel spaced from the original or first panel, which adapter comprises a strip formed to interlock with the mounting means of the original or first panel to secure the adapter in which the second glass panel is mounted in spaced relation to the first to the sash with a sealed air space between the panels.

The invention consists in the novel features and in the combinations and constructions hereinafter set forth and claimed.

In describing this invention, reference is had to the accompanying drawing in which like characters designate corresponding parts in all the views.

Figures 1 and 2 are fragmentary isometric views, partly in section, illustrating the adapter applied to different forms of sashes.

Figure 3 is a fragmentary isometric view of the metal sheath for the glazing strip shown in Figure 2.

In Figure 1, 1 designates the bottom rail of a sash originally intended to support one glass panel 2, the side rails or stiles and the top rail being substantially the same as the bottom rail 1. In the form of the sash shown in Figure 1, one of these rails, usually the top rail, is demountable for the purpose of removing and replacing the glass panel 2. In Figure 1, the sash may be wood or metal and is formed with a channel 3 opening through its inner edge for receiving the margin of the glass panel 2 and the mounting thereof. The mounting is usually formed of rubber or resilient material having a channel-shaped portion 4 located in the channel 3 and embracing the margin of the glass panel 2, and with an outer head portion 5 engaging with the glass panel outside of the channel 3.

6 designates the adapter which is formed up of sheet metal in strips of suitable lengths, each provided with a lengthwise portion 7 interlocking with the mounting means for the first glass panel 2 and also with means for supporting a second glass panel 8. As here shown, the lengthwise portion 7 is in the form of a channel embracing the margin of the glass panel 2 and seated in the channel-shaped portion 4 of the mounting for the panel 2. Also, the adapter is formed with a portion located outside the channel 3 at one side of the panel 2, this being angular in cross-section and forming the bottom 9 and one side 10 of the channel, the side 10 being opposed to the panel 2. A suitable mounting 11 is located in the angular outside portion of the adapter 6, and this includes a spacer 12 interposed between the margins of the glass panels 2 and 8. The mounting 11 is also formed with a lip 13 covering the edge of the side wall 10 of the outside channel portion of the adapter. Thus, in order to convert a single sash of this type into a double sash, the removable rail, as the top rail, is demounted, the glass panel 2 demounted, a mounting, as 4, with the head or glazing strip portion 5 located in the channel 3 of the sash, the adapter 6 then placed in position. Then the mounting 11 including the spacer 12 placed in the adapter and the glass panels 8 and 2 placed in position and the top rail, which is also equipped with the adapter, and the mountings replaced, so that a sash adapted to support a single glass panel is converted into a sash adapted to receive spaced apart glass panels.

Any known dehydrating means may be used, if desired.

In Figure 2, a form of sash for supporting a single panel is shown in which a removable glazing strip of rubber or similar material is used, which glazing strip is removable for the purpose of removing and replacing the sash instead of having one of the rails, as the top rail of the sash, demountable.

In Figure 2, 21 designates a sash shown as formed up of sheet metal to have a channel for receiving the margin of a single glass panel 22. The channel designated 23 is shown as provided with a bottom portion and with one side flange 24 and as being open at its other side, this latter side being closed by a removable glazing strip. Normally a suitable lining or mounting 25 of rubber or similar material is located in the channel 23.

26 designates a removable glazing strip of rubber or similar material, this having a base portion 27 which extends into a groove 28 located in the sash to the outer side of the channel 23 and having its open edge at substantially the level of the bottom of the channel 23. The glazing strip also has a head portion 29 which presses

against the outer side of the glass panel 22. Preferably, this glazing strip 26 is protected by a metal sheath 30 having a base portion 31 angular in cross-section extending into the groove 28 and 5 embracing the base flange 27 of the glazing strip and an outer portion 32 conforming to the outer contour of the head 29 of the glazing strip. Preferably the head 29 is formed with a lip 33 lapping over the outer edge of the sheath to cover 10 the same. The sheath 30 constitutes the subject matter of another application.

In this form of window, the glass 22 may be removed and replaced by demounting the glazing strip 26. The glazing strip or the sections thereof 15 may be readily displaced out of the groove 28, whereupon the remainder of these parts may be displaced out of the groove 30 permitting the glass 22 to be removed and replaced. This type of glazing strip may be of one piece for the entire 20 glass panel, but preferably the metal sheathing is in sections running along each side of the sash, that is, along the bottom rail, stiles and top rail, they meeting at the corners, whether the corners of the glass are square or rounding.

25 36 designates the adapter for the type of sash shown in Figure 2, this having a lengthwise angular base portion 37 fitting the channel 23 and interlocking with the mounting 25 or extending between the side walls of the channel 23 and the 30 outer side of the mounting 25. The adapter is also formed with an angular portion located outside the channel 23 on the side of the sash opposite to that on which the glazing strip 29 is located, said portion forming the bottom and side flange 39 of an angular groove for receiving a second glass panel 38. The side wall 39 of said portion is opposed to the margin of the first glass panel 22 or the mounting 25 thereof and the portion of the mounting 25 between the glass panels constitute the spacer. A suitable seat or mounting 40 of rubber for the glass panel 38 is located in the adapter 36. This adapter is preferably made up of sections meeting at the corners of the sash, whether the corners are rounding or square.

To adapt the sash for supporting a single glass panel, to carry spaced apart glass panels, the glazing strip 29, glass panel 22 and mounting 25 thereof is removed and the adapter strip seated in the channel 23. The seat or mounting 40 and the second glass panel 38 are then placed in position in the adapter strip, the mounting 25 for the glass panel 22 and the glass panel 22 are then mounted in position, and finally the glazing strip 29 replaced.

The sashes 1 and 21 are here illustrated as illustrative of standard sashes now in use for supporting a single glass panel and may be converted, by means of the adapter, into a sash for double glass panels economically and without modifying the sash.

What I claim is:

1. A window construction comprising a sash provided with means for mounting a single glass panel and an adapter for supporting a second panel, spaced from the first, comprising a strip formed with a lengthwise portion coacting with the mounting means for the first glass panel to secure the adapter to the sash and with a second lengthwise portion, angular in cross-section, forming the bottom and one side of a channel, the side being opposed to the first glass panel,

a mounting for the second panel located in said channel and including a spacer between the margins of the panels.

2. A window construction comprising a sash provided with a channel for mounting a glass panel therein, and an adapter for a second glass panel, spaced from the first, comprising a strip formed with a lengthwise portion extending into the channel and embracing the margin of the panel therein, and an outer portion extending 10 crosswise of the inner edge of the sash at one side of the first glass panel and angular in cross-section forming the bottom and one side of a channel, the side of which is opposed to the first glass panel, and the mounting for the second 15 panel located in the last channel and including a spacer between the margins of the panels.

3. A window construction comprising a sash formed with a channel having a bottom and one side wall for receiving a mounting for the panel 20 and with a groove extending along the open side of said channel, a removable glazing strip having a base flange seated in said groove, an adapter for a second panel spaced from the first, comprising a strip formed with a lengthwise side portion 25 extending into the channel along the side, and the bottom thereof, and thus interlocking with the mounting for the first panel, and an outer lengthwise angular portion forming the bottom and side of a second channel, the bottom extending across the edge of the side wall of the first channel, a portion of the mounting for the first panel serving as a spacer between the margins of the panels.

4. A window construction comprising a sash 35 formed with a channel open at one side for receiving the glass panel and with a groove located outside the channel and adjacent the same, a glazing strip of resilient compressible material having a base flange seated in the groove and a 40 head portion pressing against the glass panel, and a metal sheathing for the glazing strip having a base portion extending into the groove and interlocking with the base flange of the glazing strip and an outer portion conforming to the 45 outer surface of the head of the glazing strip.

5. A window construction comprising a sash formed with a channel open at one side for receiving the glass panel and with a groove located outside the channel and adjacent the same, a 50 glazing strip of resilient compressible material having a base flange seated in the groove and a head portion pressing against the glass panel, and a metal sheathing for the glazing strip having a base portion extending into the groove and 55 interlocking with the base flange of the glazing strip and an outer portion conforming to the outer surface of the head of the glazing strip, the head of the glazing strip having a lip covering the outer edge of the sheathing.

6. A window construction comprising a sash provided with means for mounting a single glass panel, an adapter for supporting a second panel spaced from the first comprising a strip having a lengthwise angular base portion interlocking 65 with the mounting means of the first panel, and an angular lengthwise portion forming the bottom and side of a channel with the side opposed to the first glass panel and the bottom overhanging one side of the sash.

ROY T. AXE.
